ELMER A. SPERRY, OF BROOKLYN, NEW YORK, ASSIGNOR TO SPERRY DEVELOPMENT COMPANY, OF DOVER GREEN, DELAWARE, A CORPORATION OF DELAWARE

VALVE MECHANISM FOR INTERNAL-COMBUSTION ENGINES.

Application filed July 21, 1919. Serial No. 312,193.

This invention relates to new and improved multiple expansion internal combustion engines. While the broad principles of construction, as outlined herein, are applicable to many types of internal combustion engines, the invention has perhaps its greatest application in compound engines of the Diesel or constant pressure type enabling a much lighter and cheaper engine construction giving two to three times the horsepower per pound of the present Diesel engine.

One of the objects of the invention relates to the transfer valve which controls the communication between the high and low pressure cylinders and which deals with unusually hot gases (on the order of 2,000° F. max.). It is important not only that a suitably low heat balance be maintained within the valve, but that the velocity of these hot gases rushing over the valve seat be kept sufficiently low to prevent erosion. The first of these features is accomplished by intensive cooling of the transfer valve, while the second is accomplished by cushioning the flow of the transfer gases. It will, of course, be understood that these principles of handling high temperature and compressed gases are not limited in application to compound combustion engines but have application to other types of heat engines and cycles wherein valves are employed to control the entrance of the hot working gases. In compound combustion engines a high pressure or combustion cylinder acts, of course, in two capacities, first, as a combustion space or chamber wherein the fuel is burned to produce the pressure, and second, as a means for partially expanding the working gases. The low pressure or expansion cylinder, on the other hand, operates solely as an expanding cylinder, the problem of admitting the hot gases thereto being substantially the same as in any heat engine wherein combustion takes place prior to the entry into the cylinder.

A further object is so to arrange the engine that the full benefit of cushioning is had in the low pressure cylinder. While carrying the clearances at as low a point as practicable these clearances are filled with trapped gases and brought to a pressure equal or thereabouts to the transfer pressure be-

fore or at the time the transfer valve is opened. It is not only advisable that these trapped gases should be brought to this pressure, but also that the gases so utilized should be hot, in order that when the transfer valve opens, the hot gases from the high pressure cylinder will not lose temperature to cooler gases and wire drawing will be avoided.

The invention also includes the grouping in a line of one central low pressure cylinder and two high pressure cylinders, or at least cylinder heads, in one unitary structure preferably provided with the high pressure clearances in the form of compact domes of as symmetrical a form as possible. Said head structure is preferably provided with downwardly projecting skirts forming a part at least of the cylinders proper with continuous water jackets surrounding all the high temperature regions, the jacketless points being well away from the highest temperature portions. This unitary head with its pendant cylinders is supported on columns from a bed plate and the lower parts of the cylinders may be braced or guided by the said columns.

A further object of the invention is to employ the most advantageous size and shape of clearance space for the cylinders to accomplish which I so design the high and low pressure cylinder ratios as to yield a substantially hemispherical clearance space in the former.

Other objects will appear in the following description of the invention.

Referring to the drawings wherein I have shown what I now consider the preferred forms of my invention:

Fig. 1 is a sectional side elevation of an engine constructed in accordance with my invention.

Fig. 2 is a sectional detail of the combination air-inlet and transfer valve and associated parts.

Fig. 3 is an elevation of one of the members of the said valve.

Fig. 4 is a view of the actuating mechanism of one of the said combination valves taken on line 4—4 in Fig. 1.

Fig. 5 is a sectional side elevation of one of the fuel injection valves.

Fig. 5^a is a detail thereof.

Fig. 6 is a sectional view showing a modi-

fied type of valve, in which the fuel injection valve is combined with the air-inlet and transfer valves.

Fig. 7 is a sectional view of the fuel injection valve used in this combination.

Figs. 8, 9, and 10 are enlarged details of parts of this injection valve.

Fig. 11 is an enlarged sectional detail of a portion of the device shown in Fig. 6.

Fig. 12 is a section taken on line 12-12, Fig. 6.

Fig. 13 is a fragmentary sectional detail taken approximately on line 13-13, Fig. 2.

Fig. 14 is a wiring diagram of an igniting system for the engine.

Figs. 15 and 16 are details of operating mechanism for the fuel valve shown in Fig. 5.

Fig. 17 is a modification showing the low pressure cylinder raised primarily for the purpose of shortening the passage between the high and low pressure cylinders.

In the drawings, 1 and 2 represent the high pressure cylinders, while 3 represents the low pressure cylinder; the high pressure pistons being shown at 1' and 2' and the low pressure piston at 3'. Passages 1^a and 2^a are provided for communication between each of the high pressure cylinders and the low pressure cylinder, valves 1^b and 2^b being provided to close said passages. Said valves are contained within a structure 4, which also includes the air-inlet valve hereinafter described. The fuel inlet valves are shown at 5, and a heating or igniting grid or baffle 6 may be positioned in the path of the injected fuel within each of the high pressure cylinders.

In order to produce a sufficient amount of combustible material to actuate the low pressure cylinder after the completion of the working stroke of the high pressure piston, I have shown a large clearance space 7 within each of the high pressure cylinders. This space will permit of the compression of a greater amount of air within said cylinders at each compression stroke. This in turn will permit of the injection of a greater quantity of fuel, which preferably will continue throughout a considerable portion of the working stroke of the high pressure piston, at a rate which will keep the pressure within the cylinder substantially constant during the period of injection.

In order to obtain a high degree of efficiency in the distribution and combustion of the incoming fuel, I prefer to construct the clearance 7 hemispherical or dome shaped. This shape, it will be recognized, will present a minimum surface area for a given size clearance space of combustion chamber, so that a minimum area of cooling surface is exposed to the working gases. The depth of this space may be equal to approximately one-half the diameter of the high pressure piston. In order that this shape of clearance may be employed to advantage, it is necessary that

the ratio of the displacement of the high and low pressure pistons be a predetermined value, which I have found to be in the neighborhood of one to six or more.

Preferably the fuel injection valve 5 is positioned at or near the top of the dome and substantially coaxial with the longitudinal axis of the piston within the cylinder, or at least in such manner that the axis of the stream of injected fuel is substantially coincident with said axis of the piston. This will insure a more rapid and equal distribution of fuel within the clearance space 7 and effect a more perfect combustion.

The details of one form of fuel injection valve 5 are shown in Fig. 5. This valve is of the solid fuel injection type i. e. the oil itself is placed under extremely high pressure and is forced into the cylinder without the use of compressed air as is commonly done. The fuel is forced in through a small inlet valve 10 and down through channel 11 into recess 12; thence down through channels 13 into diagonally disposed channels 14 in member 15 (see also Fig. 5^a) whence it enters recess 16 in a whirling motion. It then rises up through channels 17, 18 around the valve stem 19 and out through a safety valve 20 which is arranged to open against the action of spring 21 at a pressure somewhat less than normally maintained upon the oil. After passing out through said safety valve the oil is carried back to the fuel tank (not shown). When the valve is opened by the lifting of stem 19 against the action of spring 22 by the partial rotation of shaft 23 with arm 24 which presses upwardly against collar 25 on said stem, the swirling oil is projected into the cylinder at such a high velocity as to become highly atomized. The fuel then becomes ignited by the heat of the compressed gases within the cylinder as well as by contact with the electrically heated baffle 6. Both the time of opening of the fuel valve with respect to the cycle of the engine and the length of time during which it remains open are adapted to be varied. For this purpose I have shown shaft 23 as rocked by means of a lever 26 (Figs. 15 and 16) pivoted at 27 and having a roller 28 engaging a cam 29 on a sleeve 30 rotatable with the engine cam shaft 31. Said cam 29 is preferably in the form of a triangle as indicated by dotted lines in Fig. 16, with the advance edge 32 parallel to the axis of the shaft. Splined to the cam shaft 31 is a sleeve 33 movable longitudinally thereon by means of a handle 34 pivoted at 35 and provided with a fork 36 engaging between flanges 37 on the sleeve. The sleeve 30 is mounted upon the sleeve 33 and is movably secured thereto as by means of a pin 38 on sleeve 33 projecting into an inclined slot 39 in sleeve 30. Sleeve 30 may be moved upon sleeve 33 by means of a handle 34' pivoted at 35' and engaging between collars 37' on said sleeve 30. It will be

readily apparent that as sleeve 30 is moved longitudinally, it will also be rotated with respect to shaft 31, but if sleeve 33 is so moved with sleeve 30 no rotation of either sleeve 5 will take place. If it is desired to vary the length of time during which the fuel valve is to remain open, sleeve 33 will be actuated with sleeve 30. This will move cam 29 laterally with respect to roller 28 so that said roller will 10 have to pass over the cam at a point where the width of the latter is greater or less. The roller will thus be lifted at the same time with respect to the cycle of the engine, but will remain lifted for a longer time. By actuating 15 only sleeve 30 cam 29 will be simultaneously rotated and moved laterally, so that the time of opening of the valve as well as the length of time that it remains open will be varied. To vary the time of opening, sleeve 20 33 alone will be actuated, handle 34' being held still. This will cause sleeve 30 to rotate, due to the pin and slot connection, without moving longitudinally with respect to shaft 31. By proper manipulation of both 25 handles 34 and 34' it is evident that any desired time of opening of the fuel valve as well as the length of time during which it is held open may be effected.

The preferred details of the combination 30 transfer and air-inlet valve 4, which is shown positioned to one side of the fuel valve 5, are shown in Fig. 2. The transfer valve 1^b is shown as comprising a hollow or sleeve-like member, flaring outwardly at its lower extremity and seating against the wall 39 of the valve casing at 40°. Said sleeve is also provided with two flanges 40, 41 bearing against walls 39. The air-inlet valve 42 is shown within the sleeve-like transfer valve 1^b and 35 may be provided with spiral ribs 43 (see also Fig. 3) resting against the inside of the transfer valve at 44 and acting as a guide as well as cooling ribs for the inlet valve. Said valve is also provided with a piston 45 bearing 40 against the walls of the transfer valve at 46. The inlet valve is shown as seating against the flaring walls of the transfer valve at 47, thus closing the interior of the sleeve from 45 the high pressure cylinder.

50 The charging air which is supplied to the cylinder from a tank 48 (Fig. 1) is led in through pipe 49, and enters the valve at 50, flowing through ports 51 to the interior of the transfer valve and rushes into the cylinder 1 when the inlet valve 42 is opened. The valves are held normally closed by the pressure of the compressed air by reason that the air circulated through the valves will exert an upward and a downward pressure against 55 flange 40 on the transfer valve; a downward pressure against flange 41 and an upward pressure against the flaring portion 52. The areas of these surfaces are so proportioned that the combined upward pressures 60 will overcome the combined downward pres-

sures, thus holding the valve upwardly against its seat. The upward pressure against flange 45 will also overcome the downward pressure against the flaring portion 53, so that the inlet valve 42 will also be held 70 closed.

For actuating the valves, a pair of levers 54, 54' are provided. Lever 54 is rigidly mounted on a shaft 56 having its bearing in a bracket 57. On the opposite end of said shaft is provided a projection 58 (see also Fig. 4) engaged by a lever 59. Said lever is pivoted at 60 and carries a roller 61 engaging a cam 62 on cam shaft 31. The actuation of said lever by said cam effects the tripping 80 of projection 58 and arm 54 to depress and open valve 42. The transfer valve 53 is provided at its upper end with a circumferential groove 63, within which the ends 64 of a bifurcated arm 54' engage. Said arm is secured to shaft 56' provided with a projection 58' engaged by a lever 59' also pivoted at 60 and provided with a roller 61' actuated by a cam 62' on shaft 31. The operation in the same as in the case of valve 42. Preferably 85 the intake-transfer valve is eccentrically placed in a horizontal plane with respect to the high pressure cylinder as indicated in Fig. 13 so that the incoming air will be given a vortex or swirling motion as indicated by 90 the arrows 67 in said figure about the circular walls of the cylinder, thereby securing a uniform combustible mixture.

The cooling of the valves will be effected 95 by contact with the air circulated therein and especially by the wash of compressed air rushing into the cylinder. In order to distribute the heat from the lower part of valve 42 throughout the stem 57' thereof and ribs 43, the inside of said valve and stem may be 100 made hollow as shown and a small quantity of mercury or other volatile liquid 64' provided therein. The mercury by evaporation and condensation will cause rapid distribution of 105 heat along the valve stem where it will be 110 absorbed by the incoming air.

After the combustion of the mixture in the high pressure cylinder and the completion 115 of the working stroke of the piston therein, (the low pressure piston 3' being then in the upper position as shown in Fig. 1) the transfer valve 1^b is designed to open and permit the gases to flow into the low pressure cylinder to force the low pressure piston down on its working stroke. At the end of this stroke 120 the transfer valve will close and the exhaust valve 65' in the low pressure cylinder will open, permitting the gases to flow out through openings 66 and escape. In the mean time the opposite high pressure cylinder, as 125 for instance cylinder 2, will have been repeating the functions of cylinder 1 so as to be ready to discharge its partially expanded gases into the low pressure cylinder as soon as piston 3' reaches its upper position again. 130

When at the end of the up stroke of the low pressure piston and the down stroke of the high pressure piston the transfer valve opens and permits the partially expanded gases to pass into the low pressure cylinder, ordinarily there would be a sudden rush of the highly compressed and heated gases through passages 1^a or 2^a into said low pressure cylinder. The pressure in the high pressure cylinders rises to 400 pounds or more per square inch. The shock of this sudden inrush would tend to produce jerky action on the part of the engine, while the intensely high velocities at the instant of opening would cause pitting and erosion of the valve seats. Moreover, too sudden expansion of the gases would be attended by a corresponding loss of energy. To overcome these objections compressed air or other gases may be supplied to the clearance space 3^a in the top of the low pressure cylinder and passages 1^a, 2^a, substantially equal to the pressure of the gases in the high pressure cylinder at the moment of opening of the transfer valve. In addition, there are more or less remote chambers such as annular chambers 52' within the valves which must be filled with gas through said passages 1^a and 2^a and brought up to transfer pressure at the time of opening the transfer valve, as well as the main clearance space. Such passages and remote chambers naturally require more time to fill than the main clearance space and hence in order to fill the same it is essential that the rise in pressure be gradual. Also, of course, such passages and chambers serve to increase the volume of the clearance space to be filled at the time the transfer valve is opened, so that, if the pressure in said space is materially less than the pressure in the combustion cylinder, a large volume of white hot gas rushes over the transfer valve to fill it. Preferably this compressed gas is supplied by closing the exhaust valve 65' of the low pressure cylinder before the end of the exhaust stroke of the piston, so that the gas then remaining in the cylinder will be compressed by the remainder of the up stroke. Upon the opening of valve 1^b then the transfer of gases will take place smoothly. It is also preferred that the temperature of this compressed or cushioning gas in the low pressure cylinder should be of substantially the same temperature as the transfer gases. In this connection it will be recognized that while the gas loses a great deal of heat in work, it will still possess considerable heat at the completion of its work, so that when a portion of it is again highly compressed the heat reacquired along with the heat retained will be considerable.

At this point attention is called to the full and unique significance of cushioning as it is applied to this invention in its relation to the peculiar and novel cycle operation disclosed herein. The facts are that the transfer valve is required to handle gases at temperatures

and pressures heretofore thought impossible and never before successfully accomplished in the art. Nor has a valve in any high pressure combustion engine ever been called upon to handle the very large volume of gases present in this cycle in which my high pressure chamber may handle from six to seven times the volume of gases handled by the Diesel engine of similar displacement. To illustrate what I am enabled to accomplish by the correct application of cushioning under these critical conditions let us for the moment consider that the ordinary exhaust valve of an explosion or Otto cycle engine were opened at the highest pressures and temperatures reached after ignition where the temperatures are probably above the melting point of platinum and the pressures are on an equality with the transfer pressure in my cycle. Upon the first breaking away of the valve from its seat the white hot gases start and rush over these delicate fitting surfaces with an enormous velocity—about 4 miles per second. This, together with the terrific heat present, causes serious erosion of these surfaces and they are almost instantly riddled with deep furrows and the surfaces of both valve and seat are literally washed away and disappear exactly as do the inner surfaces of the nozzle of heavy ordnance and from the same cause, namely the high velocity escape of the hot gases as the rear end of the locking ring and shell emerges from the gun. How long would this gun nozzle last if we fired at the rate of several rounds per second as is the case with my transfer valve? I have succeeded in meeting this almost impossible situation, have overcome the difficulty, and have been able to secure practical operation of these valves, so vital to successful performance by compelling the low pressure cylinder in the latter part of its exhaust stroke to act as a high pressure compressor. By selecting a critical point for closing the exhaust valve the piston is caused to trap and compress the hot products of combustion to the exact pressure of the gases in the high pressure cylinder at the instant of opening the transfer valve. Under these conditions no flow whatever takes place upon the breaking away of the valve from its seat and not until the valve is almost completely open and then the gases slowly start to flow only as the piston slowly starts on its outward stroke. The flow is under perfect control and is limited in velocity which is actually much less than the outward speed of the piston owing to the extremely large low pressure volume and the correspondingly large proportion of the total expansion of the gases, all of which takes place after they have passed the transfer valve and entered the cylinder.

A complete cycle of operation of the engine, therefore, is as follows: On the down stroke of high pressure piston 1' air is drawn

into the cylinder through the air induction valve. On the up stroke of piston 1' the air is compressed to a high degree of compression sufficient to heat the air so as to cause ignition when mixed with fuel. Near the end of the upper stroke of piston 1', fuel is injected through the fuel injection valve and the mixture ignited. A power stroke is now obtained on the down stroke of piston 1'. On the return upward stroke of said piston the transfer valve between the high and low pressure pistons opens and the upward movement of piston 1' causes discharge of the mixture into the low pressure cylinder. The high and low pressure pistons being 180° out of phase, the expanding mixture entering the low pressure cylinder as piston 1' rises causes the descent of the low pressure piston. On this power stroke of the low pressure piston air is compressed by the pump 104 to supply compressed air to the air reservoir. Since the pistons 1' and 2' are 360° out of phase, the low pressure piston will receive a power stroke on each of its downward movements because each fourth stroke of pistons 1' and 2' is effective and these strokes are 360° out of phase.

Referring now more specifically to the fuel igniting means 6 in the high pressure cylinders, the coil may be somewhat umbrella-shaped so that the incoming oil spray represented by dotted lines 68 may be thereby distributed equally throughout the cylinder and be more completely vaporized as well as ignited. Current is led into and away from the coil by means of wires 69, 70 secured in a plug 71. For supplying the current I have shown in Fig. 14 a motor generator 72, comprising a motor 73 and a low voltage high current generator 74 having a separately excited field, the terminals of which are indicated at 75, 76. The motor and the fields of the generator are excited from line wires 77, 77', wire 77' being connected to the generator through a rheostat 78, while current from the armature of the generator is carried directly to the heating coils 6, 6'; one side of the armature and one side of each coil being grounded. The strength of the generator fields is automatically controlled so that the current supplied to the heating coils may be governed in accordance with the requirements of the engine. Handle 79 represents the control handle of the engine for starting and operating the same. The full line position is the starting position and the dotted line position the running position. On the shaft 80 of said handle is an arm 81 having a lug 82 bearing against the fuel control lever 83. As the control handle 79 is moved in a counterclockwise direction to the full line position the fuel handle 83 will be likewise moved, but when the handle is moved back to the running position the fuel handle will remain in the full line position. Connected to the fuel handle by

a link 84 is a switch 85 in circuit with a solenoid 86. A lever 87 is also connected to link 84 to actuate a second switch 88 in circuit with rheostat 78. As the fuel handle is thrown to the position shown it will be seen that both switches are closed. The closing of switch 88 will cause the excitation of the fields of generator 74 to a greater or less degree depending upon the position of the arm 89 of the rheostat 78. Said arm is normally pulled downwardly by a spring 90, while the core 91 of solenoid 86 serves to pull the arm upwardly against the action of said spring. Said solenoid may be excited as shown by means of a battery 92 and has in circuit therewith in addition to switch 85 a resistance coil 93 positioned as shown in the various figures within the clearance 7 of the high pressure cylinders. This circuit is also grounded as shown at 94 and by being connected to wire 70. Said coil is composed of material having a high temperature resistance coefficient such as nickel or a nickel alloy. Since the battery 92 has a constant E. M. F. it will be seen that the strength of the solenoid will vary in accordance with the resistance of coil 93 and hence in accordance with the temperature thereof. The temperature of the coil 93, moreover, depends directly upon the temperature within the high pressure cylinder so that the hotter the coil becomes, by reason of the heat within the cylinder, the less current flows through the solenoid and hence the greater the resistance interposed by rheostat 78. This weakens the fields of generator 74 and hence lessens the current supplied to coils 6, 6'. Thus, when the engine is starting or at other times when the interior of the combustion cylinders are not sufficiently hot to insure proper combustion, a large amount of heat will be supplied through coils 6, 6' upon which the injected fuel will impinge, but as the heat of the cylinders increases, the introduced heat will decrease in proportion to the decreasing necessity therefor.

In the construction of the engine, the top member 95 which embraces the tops or heads of all of the cylinders including the dome-shaped clearances 7 of the high pressure cylinders and the flat clearance 3^a of the low pressure cylinder is provided with downwardly extending skirts or hollow cylinders 96, 96', 97, which form the upper portions of the high and low pressure cylinders. By this means the joints 98 between the top member 95 and the lower portion 99 of the cylinders which are necessarily without water jackets are removed from the hottest portion of the cylinder to a much cooler portion, i. e. near the bottom of the cylinder. The water jacketing of the cylinders is also greatly simplified thereby. It will be seen by this construction that the cylinders are suspended from the top member 95. Said

top member, on the other hand, is supported above the bed plate 100 by means of end columns 101 and central columns 102.

For supplying compressed air to tank 48 I prefer to employ the outer end 103 of the low pressure piston in cylinder 3 as a compressor. By this means a great saving in weight and a higher efficiency of the engine are effected. For this purpose the outer end 10 of cylinder 3 is closed by a hollow ring 104 in which the inlet and outlet valves 105, 106 are contained; the air being discharged by way of said outlet valve into said tank 48. It should be observed that the effective displacement of the pump piston 103 is somewhat less than that of the low pressure piston 3' due to the large downwardly extending trunk 103' surrounding the piston rod 150' of the low pressure piston and slidably mounted in the guide 151'. The effective displacement of said piston is also substantially greater than that of either one of the high pressure pistons 1' or 2' and in fact substantially greater than, i. e. preferably more than double, the combined displacement of the said pistons. In the engine illustrated the relative displacements of the pistons are approximately as follows, taking the displacement of each high pressure piston at unity:

Displacement of the high pressure pistons, each, 1. Combined displacement, 2. This displacement, of course, applies both to the second compression stage and the first expansion stage as both of these stages take place within the same cylinder and on the same side of the piston.

Displacement of the low pressure piston (second expansion stage), 6.

Displacement of the pump piston (first compression stage), 5.

In order to regulate the amount or pressure of air delivered to the cylinders, the pressure maintained in tank 48 may be varied, which in turn may be accomplished by varying the clearance in the compressor end of cylinder 3. For this purpose I may employ a piston 107 working in a cylindrical chamber 108 opening into the outer or compressor end of cylinder 3. During the down stroke of piston 3', compressing air and discharging the same into tank 48 through pipe 109 a part of the air will be compressed into chamber 108. On the upstroke of piston 3' when valve 106 closes the air compressed in chamber 108 will expand into cylinder 3 and thus limit the amount of air sucked into the compressor. Obviously, by decreasing the amount of air drawn into the compressor, the amount of compressed air delivered is also decreased. Said piston 107 is provided with a stem 110 passing through bevel gear 111 and threaded thereto. A second bevel gear 112 meshes with gear 111 and is provided with actuating means such as a

handle 113 on its shaft 114. The turning of handle 113 will cause stem 110 to screw down or up through bevel gear 111 and adjust the piston 107. By providing an electric motor 115 having a bevel gear 116 meshing with gear 112 the position of piston 107 may be readily controlled through such means.

In Fig. 6 I have shown a modified form of the invention in which the fuel valve is combined in the same unitary structure with the air-inlet and transfer valves.

In this form the valve unit 4' is shown in the top central part of the dome of the high pressure cylinder 1' and having its axis coincident with that of said cylinder and may be secured by bolts 129. The transfer valve is shown at 120, the air-inlet valve at 121 within the transfer valve and the fuel valve 122 within the inlet valve (see Fig. 7).

The compressed air charge is brought in through opening 123, and as in the previous forms, the various surfaces *a*, *b*, *c*, and *d* are so proportioned that the upward pressure of this air upon the valve predominates and holds the transfer valve normally closed. Similarly the downward pressure on the surface *e* of valve 121 is overcome by the upward pressure against flange 124 secured adjacent the top of the stem 125 of said valve by nuts 126, so that the inlet valve is normally held closed. The sliding engagement between the flange 124 and the upper part of the transfer valve at 131 is, of course, airtight as is also the engagement between said transfer valve and the valve casing 39' at 132, 133. Numerous radiating fins 127 may be provided on valve 121 and the lower part of the stem 125 thereof, which, being swept by the incoming air which also sweeps over the valve head itself, will cool the head of the inlet valve. Some of these cooling fins, as for instance 127', may extend high enough to engage the inner surface of the transfer valve as at 128 to act as a guide for the inlet valve. The transfer valve 120 will be cooled by the wash of the air over all of its interior surface. In this connection, the lower part of this valve, within the space containing the air may be provided with cooling fins 130 for more intensely cooling the lower part of the valve which is, of course, the part subjected to the most heat. Guides 134 may be provided on the transfer valve engaging casting 39'.

In Fig. 7 the air-inlet valve is shown in section to display the fuel valve. The hollow stem 125 of the air valve is shown as comprising part of the conduit through which the fuel is carried to the cylinder. The fuel is in turn led into this stem by means of a flexible tube 135. This tube is secured at one end in a terminal 136 secured to the piston-like flange 124 (Figs. 6 and 11), into which a second tube 137 leads. The fuel valve 122 is seated on a member 138 located in the lower

part of stem 125 and held in place by a threaded member 139 (see also Fig. 10). The said member 139 is provided with an opening 140 for the fuel to pass through; the opening 5 being smaller if desired at its lower end as shown at 141. Within the opening 140 I have shown a plug 142, shaped to a point 143 on the upper side to spread the oil to the outer edges. The periphery of the plug may 10 be provided with diagonally cut grooves 144 to transmit to the fuel passing therethrough under pressure a swirling motion for the purpose of atomizing it. The fuel then issues through the small opening 141 in a spreading 15 spray which is more or less axially projected by reason of said small opening and which is intercepted by the coil 6 with the results hereinbefore pointed out. Among the advantages of this type of structure are that in 20 addition to cooling the valves by the incoming air, the air-inlet valve is further cooled by the incoming fuel. In both instances, instead of dissipating the heat absorbed by the valves, it is transferred to the incoming elements of combustion and utilized, and is a 25 conservation of so much energy. In order to aid the transfer of heat from the valve to the oil and to assist in setting member 138, guide columns 145 may be provided on member 138 30 reaching up into stem 125 and resting against walls thereof. I may also provide guide members 146 (Figs. 7 and 8), between said vanes 145 at the base thereof forming a beveled segmental ring to guide the oil directly through the valve opening. The stem 35 147 of the fuel valve reaches up through hollow stem 125, passing slidably through member 148 and having a sufficiently close fit therewith to prevent leakage of oil. Member 148 40 in turn rests against the inner wall of stem 125 with packing 149 and held in place by member 150 screwed into said hollow stem.

The following means are provided for actuating the valves: Flanges 151, 152 are 45 provided on the upper part of the transfer valve 120, between which flanges the bifurcated ends 153 of lever 154 engage. Said lever is pivoted at 155 to a bracket 156 secured to the top of the engine. The outer end 50 157 of lever 154 is provided with a roller similar to roller 158 and hidden thereby which is adapted to be engaged by a cam 159 on cam shaft 31'. The piston-like flange member 124 on the upper end of the air-inlet stem 125 is provided with a smaller upper flange 160 and is engaged by the bifurcated end 161 of a lever 162 having a roller 158 engaging cam 163. Said lever is pivoted to a link 164 which is in turn connected to lever 154, so 55 that when cam 163 raises lever 162 to open valve 121 an upward force will be applied to valve 120 through link 164 and lever 154. The top of stem 147 of the fuel valve is provided with flanges 165, 166 between which 60 65 the bifurcated end 167 of a bell crank lever

168 engages. Said lever is pivoted to a bracket 169 projecting upwardly from flanges 124, 160 and is connected by a link 170 to a lever 171 pivoted at 172 to bracket 156 and carrying a roller 173 adapted to be engaged by cam 70 159 to open the valve. A tension spring 174 connected at one end to lever 168 and at the other to arm 175 reaching out from bracket 169 serves to hold the fuel valve normally closed. 75

In Fig. 17 I have shown a slight modification in the position of the low pressure cylinder. In this modification the low pressure cylinder 176 is shown as raised so that the passage 177 leading thereto from the high pressure cylinder will run straight across as 80 shown instead of diagonally downward as shown at 177', in Fig. 8. This passage will thus be made as short and as direct as possible.

In accordance with the provisions of the 85 patent statutes, I have herein described the principle of operation of my invention, together with the apparatus, which I now consider to represent the best embodiment thereof, but I desire to have it understood that the 90 apparatus shown is only illustrative and that the invention can be carried out by other means. Also, while it is designed to use the various features and elements in the combination and relations described, some of these 95 may be altered and others omitted without interfering with the more general results outlined, and the invention extends to such use.

Having described my invention, what I 100 claim and desire to secure by Letters Patent is:

1. In a combustion engine having means for compressing the air supply to the combustion cylinder, a clearance space of large capacity for said cylinder, a solid injection fuel 105 feeding device operating during a portion of the expansion stroke within the said combustion cylinder, the axis of the said solid injection stream being substantially coincident with the longitudinal axis of the piston, and 110 induction and eduction valves leading to said clearance space located at one side of the said axis, and tangentially disposed with reference to such axis for inducing vortex action within the cylinder. 115

2. In a combustion engine having means for compressing the air supply to the combustion cylinder wherein the compression rises to 400 pounds or more per square inch, a clearance space for such cylinder with a circular portion having a depth approximating half the piston diameter, a fuel feeding device communicating with such portion of the clearance, and an induction port for said compressed air tangentially arranged with 125 reference to such circular portion for producing a vortex action within such space. 120

3. In a combustion engine having means for compressing the air supply to the combustion cylinder wherein the compression 130

- rises to 400 pounds or more per square inch, a clearance space for such cylinder with a circular portion having a depth approximately half the piston diameter, a fuel feeding device communicating with such portion of the clearance, and a combined induction and exduction valve tangentially arranged with reference to such circular portion for producing a vortex action within such space.
10. 4. In a multiple expansion gas engine, the combination with a high and a low pressure cylinder, of a transfer valve therebetween, an exhaust valve for the low pressure cylinder, means for operating each valve, said valves being so timed that the exhaust valve closes prior to the opening of the transfer valve and before the low pressure piston completes its return stroke.
5. In a multiple expansion internal combustion engine, the combination with a pair of high pressure cylinders and a common low pressure cylinder, and transfer valves, of means for bringing the pressure and temperature in the latter cylinder up to approximately the pressure and temperature of the transfer gases before or at the time the respective transfer valve is opened.
6. In a multiple expansion internal combustion engine, the combination with the high and low pressure cylinders, transfer and exhaust valves therefor, of means for closing the exhaust valve of the low pressure piston on the return stroke thereof and prior to the opening of the respective transfer valve whereby the pressures are equalized.
7. In a vertical compound internal combustion engine a cylinder head or cap constituting a unitary structure containing three cylinder heads consisting of two high pressure and one low pressure, the said cap providing two dome or hemispherical clearance spaces for the high pressure cylinders, each communicating with the central or low pressure cylinder and means for suspending said cap from adjacent the top thereof.
8. In a vertical compound internal combustion engine a cylinder head or cap constituting a unitary structure containing three cylinder heads consisting of two high pressure and one low pressure, the said cap providing two dome or hemispherical clearance spaces for the high pressure and a flat top clearance space for the low pressure cylinder and means for suspending said cap from adjacent the top thereof.
9. In a vertical compound internal combustion engine a cylinder head or cap constituting a unitary structure containing three cylinder heads consisting of two high pressure and one low pressure, each head having a skirt projection extending downwardly, so as to provide in part walls for said cylinders, means for suspending said cap from adjacent the top thereof and a detachable lower portion secured to said skirt whereby the piston
- may be removed and disassembled without taking down the engine.
10. In a vertical compound internal combustion engine, a unitary cap plate, including cylinder heads for each cylinder and a portion of the walls of each cylinder, water jackets therefor, a lower portion also having a water jacket of each cylinder detachably secured to said cap, the joints between said portions and the caps being situated below the hottest portions of the cylinders but above or in line with the top of the piston when in its lowermost position and means for suspending said cap from adjacent the top thereof.
11. In an internal combustion engine, the combination with the cylinder, of inwardly opening combined intake and exhaust valves, a source of compressed air for the intake and a piston on each valve subject to the pressure of said air for holding each valve outwardly against its seat.
12. In a multiple expansion internal combustion engine, the combination with a high and a low pressure cylinder, of an inwardly opening hollow transfer valve located in the clearance of the former cylinder, and an inwardly opening intake valve therefor having a hollow stem mounted and seated within said transfer valve whereby the intake air flows around and down the said stem, the last named valve being adapted to contain a volatile liquid whereby the heat of the end of the valve is transferred to the air cooled stem.
13. In an internal combustion engine in which the intake air is precompressed, a high pressure cylinder, a low pressure cylinder, a transfer valve for transferring the partly expanded heated gases from the high pressure to the low pressure cylinder, two pistons thereon, one of which is the larger, and an inlet for said air between the pistons to hold said valve on its seat.
14. In an internal combustion engine in which the intake air is precompressed, a high pressure cylinder, a low pressure cylinder, a transfer valve for transferring the partly expanded heated gases from the high pressure to the low pressure cylinder, two pistons thereon, means for introducing said air between said pistons and for causing a circulation thereof in contact with said valve whereby said valve is both cooled and held on its seat thereby.
15. In an internal combustion engine in which the intake air is precompressed, a high pressure cylinder, a low pressure cylinder, a transfer valve for transferring the partly expanded heated gases from the high pressure to the low pressure cylinder, two pistons thereon, means for introducing said air between said pistons, and a concentrically mounted intake valve within said transfer valve in communication with said air.

16. In a multiple expansion engine in which the intake air is precompressed, a transfer valve, a valve seat therefor, an intake valve seated thereon, a piston on said intake valve subject to the pressure of the intake air for holding both the valves on their seats, and a piston on said transfer valve subject to said pressure for holding the same on its seat when the intake valve is opened.
17. In a multiple expansion engine in which the intake air is precompressed, a transfer valve, an intake valve, one of said valves being seated on the other, a piston on the valve which is seated on the other valve for holding both valves on their seats, and a piston on the other of said valves for holding it on its seat when the first named valve is opened.
18. In a combustion engine having means for compressing the air supply to the combustion cylinder, the combination with a combustion cylinder wherein the compression rises to 400 pounds or more per square inch, a clearance space for such cylinder having a depth approximating half the diameter, an expansion cylinder, a transfer valve between said cylinders, an exhaust valve for the expansion cylinder, and means for closing the latter before its piston reaches the end of its stroke whereby the pressure in the two cylinders is rendered substantially equal at the time the transfer valve is opened.
19. In a multiple expansion internal combustion engine, the combination with the high and low pressure cylinders, transfer and exhaust valves therefor, the low pressure cylinder having a remote passage or chamber connected with the clearance space thereof, of means for closing the exhaust valve on the return stroke of the low pressure piston and prior to the opening of the transfer valve whereby the pressures are equalized.
20. In a combustion engine having means for compressing the air supply to the combustion cylinder, the combination with a combustion cylinder wherein the compression rises to 400 pounds or more per square inch, a clearance space for such cylinder having a depth approximating half the diameter, an expansion cylinder of at least four times the capacity of the combustion cylinder, a transfer valve between said cylinders, an exhaust valve for the expansion cylinder, and means for closing the latter before its piston reaches the end of its stroke whereby the pressure in the two cylinders is rendered substantially equal at the time the transfer valve is opened.
21. In a heat engine, the combination with a working cylinder for expanding the hot gases, of an intake valve therefor, means for cooling the same by the circulation thereover of cooler fluid, and means for bringing the pressure within said cylinder substantially up to the pressure of the entering gases at the time said valve is opened.
22. In a heat engine, the combination with a working cylinder for expanding the hot gases, of an intake valve therefor, means for cooling the same by circulation thereover of cooler fluid after each passage of the hot intake gases, and means for bringing the pressure within said cylinder substantially up to the pressure of the entering gases at the time said valve is opened.
23. In a heat engine, the combination with a combustion space where hot products of combustion are developed, of a separate cylinder for expanding the hot gases, an intake valve therefor, fluid means for cooling the same, and means for bringing the pressure within said cylinder substantially up to the pressure of the entering gases at the time said valve is opened.
24. In a heat engine, the combination with a combustion space where hot products of combustion are developed, of a separate cylinder for expanding the hot gases, a combined intake valve for said combustion space and intake valve for said expanding cylinder whereby said valve is kept cool by the incoming gases to said combustion space, and means for bringing the pressure within said cylinder substantially up to the pressure of the entering gases at the time the first named intake valve is opened.

In testimony whereof I have affixed my signature.

ELMER A. SPERRY.
